TYPE CASTING MACHINE

Robert J. Woodruff, Duluth, Minn.

Application January 30, 1936, Serial No. 61,594

3 Claims.

The invention relates to a type casting machine and more particularly to a printing plate casting apparatus.

The primary object of the invention is the provision of a machine or apparatus of this character, wherein through the assembly of matrices within a casting box a type plate can be readily and easily formed and in this manner eliminating the necessity of the setting of individual type for the production of a form as in the setting of type it is required to handle a stick and also the blocking out with spacing material and thus by the use of the machine or apparatus a type plate can be created with dispatch and with minimum labor.

Another object of the invention is the provision of a machine or apparatus of this character, wherein the same in its construction is novel in form so as to render it readily portable, easy to handle and assuring dispatch in the making or producing of type plates for form printing.

A further object of the invention is the provision of a machine or apparatus of this character, which is simple in its construction, thoroughly reliable and efficient in its purpose, minimizing procedure in the printing art, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a front elevation of a machine or apparatus constructed in accordance with the invention.

Figure 2 is a sectional view on the line 2-2 of Figure 1 looking in the direction of the arrows.

Figure 3 is a top plan view.

Figure 4 is a sectional view on the line 4-4 of Figure 3 looking in the direction of the arrows.

Figure 5 is a perspective view of the hold-down or follower plate.

Figure 6 is a perspective view of the stick employed with the machine or apparatus.

Figure 7 is a fragmentary vertical sectional view showing a slight modification of the invention.

Similar reference characters indicate corresponding parts throughout the several views in the drawing.

Referring to the drawing in detail, A designates a base from which rises spaced perpendicu-

(Cl. 22-2) lar uprights or posts 10 in which are fitted pivots 11 swingingly connecting a casting box 12 between said uprights or posts. This casting box 12 has formed therein a cavity 13 which opens through one side of said box and adapted to be located within this cavity is a group of stacked matrices 14, each having the letter or numeral forming face 15 so that when molten lead or type material in a pouring state is delivered into the cavity 13 a printing plate 16 having a raised type face will be created.

The cavity 13 at one side thereof is confronted by a printer's stick receiving notch 17 for accommodating a stick 18 of that type employed by printers when setting individual type; it being preferable to have the stick 18 of wedge formation so that when the type material freezes within the casting box easy removal of the plate 16 is assured. The bottom of the stick 18 is tapered towards its leading edge as may be seen by an inspection of Figures 2 and 6. Such an arrangement assists in the positioning of the stick, the maintaining of the stick in its proper position and the removing of the stick.

Adapted to be superimposed upon the group of matrices 14 as confined within the cavity 13 in the box 12 is a hold-down or follower block or plate 19, it having a pouring hole 20 so that when the molten type forming material is poured from a ladle it can flow through the hole 20 beneath the block or plate 19 for the formation of the type plate through the instrumentality of the matrices 14 within the cavity 13 of said box.

Bridging the box 12 at the open side of the cavity 13 is an adjustable yoke 21, it having the notches 22 for engagement with retaining pins 23 externally of the box 12 and projecting from opposite flat sides thereof. This yoke 21 has integrally joined therewith a turn buckle extension rod 24, it being sectional and one section is carried by the yoke while the other section is engaged with the follower plate or block 19 which latter at opposite ends carries guide ears 25 operating in key ways 26 in opposite walls of the cavity 13 of the box 12. By adjustment of the turn buckle extension rod 24 the block or plate 19 can be clamped in place superimposed upon the matrices 14 to hold the same grouped and in casting position for the casting of a type plate 16 for form printing work.

Adapted to be placed upon the base A is a heater 27, the flame from its burner 28 being positioned for play upon the casting box 12 to heat the contents of the cavity 13 in the formation of the type plate.

50

55

In Figure 7 of the drawing there is shown a slight modification wherein the casting box 29 has held within its cavity 30 a cone or filler piece 31 for effecting in the type plate 32 a filling space 33 for type matter where it is required to change the printing form other than that cast with the said plate 32.

The purpose of heating the casting box 12 to the proper degree is to prevent the cast type plate 16 from becoming chilled too quickly which would result in a poor cast, the heater being of any approved type.

In the use of the machine or apparatus it is, of course, understood that the stick 18 is adapted to accommodate the matrices in the setting thereof similarly to the hand setting of individual type and after the setting of the matrices the stick 18 is placed within the notch 17 in the cavity 13 of the casting box 12 as is clearly shown in Figure 2 of the drawing and then such group of matrices 14 are clamped by the plate or block 19 and finally the molten type forming material is poured as above set forth for the creation of a type plate for form printing purposes.

The casting box 12 is held in a position to have the cavity 13 open uppermost through the medium of a releasable latch 34 which is fitted in one of the uprights 10 rising from the base A of the machine or apparatus. When the latch 34 is released the box 12 can be turned over for the delivery of the cast type plate 16.

What is claimed is:

1. A type casting machine comprising a casting box having a cavity therein, a printer's stick having a bottom, two closed ends, one closed side and one open side, said stick having a thickness less than the width of the cavity in the casting box and adapted to be received by said cavity with the bottom of the stick engaging one side wall of the cavity and being spaced from the opposite side wall of the cavity and having its closed side resting on the bottom of the cavity and the open side of the stick facing the open end of the cavity, said stick adapted to receive a plurality of matrices in stacked formation with the lowermost matrix resting upon the closed side of the stick, the letter forming faces of the matrices facing said opposite side wall of the cavity and

being spaced therefrom, the portion of said cavity not occupied by the stick and matrices adapted to receive molten lead, whereby the lead is brought into contact with the letter forming faces of the matrices.

2. A type casting machine comprising a casting box having a cavity therein, a printer's stick having a bottom, two closed ends, one closed side and one open side, said stick having a thickness less than the width of the cavity in the casting box and adapted to be received by said cavity with the bottom of the stick engaging one side wall of the cavity and being spaced from the opposite side wall of the cavity and having its closed side resting on the bottom of the cavity and the open side of the stick facing the open end of the cavity, said stick adapted to receive a plurality of matrices in stacked formation with the lowermost matrix resting upon the closed side of the stick, the letter forming faces of the matrices facing said opposite side wall of the cavity and being spaced therefrom, the portion of said cavity not occupied by the stick and matrices adapted to receive molten lead, whereby the lead is brought into contact with the letter forming faces of the matrices, the bottom of said stick being tapered in the direction of its movement into the cavity in the casting box.

3. A type casting machine comprising a casting box having a cavity therein, a printer's stick having one open side and a thickness less than the width of the cavity in the casting box and adapted to be received by said cavity with the bottom of the stick engaging one side wall of the cavity and being spaced from the opposite side wall of the cavity, said stick adapted to receive a plurality of matrices in stacked formation with the letter forming faces of the matrices facing said opposite side wall of the cavity and being spaced therefrom, the portion of said cavity not occupied by the stick and matrices adapted to receive molten lead, whereby the lead is brought into contact with the letter forming faces of the matrices, the bottom of said stick being tapered in the direction of its movement into the cavity in the casting box.

ROBERT J. WOODRUFF.
